FOURDRINIER PAPERMAKING MACHINE

Everett W. Clem, Shrewsbury, Mass., assignor to
 Rice Barton Corporation, Worcester, Mass., a
 corporation of Massachusetts

Application July 28, 1944, Serial No. 546,956

5 Claims. (Cl. 92—44)

1

This invention relates to a Fourdrinier paper making machine and more particularly to the breast roll section thereof.

In a standard paper making machine, the endless wire on which the paper web is laid passes from a breast roll over a set of table rolls and ultimately returns beneath the table from an end couch roll to the breast roll. The table rolls are customarily mounted on side bars which are arranged to be shaken so as to move the rolls endwise and aid in laying the paper fibres. The breast roll may be mounted either on the side bars or on a separate pedestal and so arranged that it too may be shaken endwise with the table rolls. In a narrow machine, the table rolls may be about 4 inches in diameter, while in a wide machine they may be 10 to 12 inches in diameter. They are customarily placed quite close together so as to give proper support for the wire and to aid in the removal of the water from the pulp thereon. The breast roll, about which the wire passes as it comes from the rear of the machine, is made of large diameter to prevent breaking or injuring the wire, and usually its diameter has been in the range of from 20 to 28". Hence the center of the breast roll must be located at a considerable distance from the first table roll, and there is a corresponding distance between the tops of the rolls which contact tangentially with the wire. Consequently, the wire is unsupported for a space of 15 to 18 inches. The suspension of paper pulp in water usually flows from a head box and over an apron onto the wire on a line located over the breast roll. The weight of the pulp on the unsupported portion of the wire between the breast roll and the first table roll causes the wire to sag, and so creates a serious problem in that the pulp will run out at the sides of the wire through the hollow that is formed.

One remedy for this has been to support the wire between these first two rolls by means of a stationary board over which the wire drags. But this creates friction and unduly wears the wire and so requires frequent replacement or reconditioning of the parts. Various other arrangements of the breast and table rolls and the slice have been made but they have not satisfied the present requirements. For example, the top of the breast roll has been located about an inch below the plane of the wire on the table rolls; but this has involved the same wide separation between the tops of the breast roll and the first table roll. Also, the slice has been arranged in various positions, such as over a table roll, but the weight of the pulp has been carried on the comparatively long stretch of wire between the

2

large diameter breast roll and the first table roll. In some cases, the pulp has been flowed onto an uphill portion of the wire, where the breast roll has been located at a lower level than the table rolls. This uphill movement, as well as a waterfall from a high apron onto the wire, should be avoided for most methods of fibre laying. It is desirable that the pulp issue in a substantially horizontal direction immediately onto the wire and in the direction in which the wire is traveling. That is, the apron on which the pulp flows from the head box should be in substantially the plane of the top surface of the wire so that the pulp will travel forward without undue agitation.

The primary object of this invention is to overcome these problems and to reduce the diameter of the breast roll, or the first roll in the table section beneath the apron, so that it will approximate the diameter of the table rolls and still be of sufficient size to be able to resist the pull or tension load created by the wire, and to so locate and arrange the parts that the unsupported length of wire at this point is reduced to a minimum consistent with good operating practice, so that the wire will not sag materially or require a supplemental support. Further objects will be apparent in the following disclosure.

In accordance with my invention, I have eliminated the large diameter roll, usually known as the breast roll, whose top is located in the plane of the wire, and I have provided a return wire roll or rolls located well below the plane of the wire and entirely remote from the paper laying zone so that this return roll does not in any way interfere with the paper laying operation. In place of that breast roll, I have provided a first table roll of the same, or preferably a somewhat larger size than the other table rolls, which is so located relative to the second table roll as to provide only a very narrow and straight run of the wire which need not be supported by any further supplemental device. The apron over which the paper stock flows from the head box to the wire is so located as to discharge the stock onto the wire adjacent to that first table roll. The apron is preferably arranged close to and substantially in the plane of the top run of the wire, and the slice is so located that the stock flows smoothly onto the wire and preferably in a direction which is substantially parallel with the plane of the wire.

Referring to the drawings which illustrate preferred embodiments of this invention:

Fig. 1 is a somewhat diagrammatic side eleva-

tional view of the forward end of a Fourdrinier machine having a single large return roll; and

Fig. 2 is a similar view showing three rolls arranged to return the wire.

The machine shown in Fig. 1 may be so constructed that the top run of the wire 10 on which the paper stock is first laid is supported on a set of closely arranged table rolls 12 suitably carried on bearings mounted on two parallel side bars 14. The table rolls 12 may be of suitable size depending upon the width of the wire, such as 10" in diameter for a wire that is 200" wide. These rolls are located as close together as is required for supporting the wire properly and aiding in the removal of the water from the pulp carried thereon. The side bars 14 are preferably carried on uprights 15 so arranged that the table rolls may be shaken endwise in accordance with standard practice. The side bars and supports 15 are carried by side frames 16 pivotally mounted at the breast roll end on the pivot bearing 17 carried by a standard 18, all of which parts are suitably arranged in accordance with standard practice. The parts may be shaken by a suitable construction, such as that shown in the patents to Kendall et al. #1,844,580 of February 9, 1932, and Vedder et al. #1,771,452 of July 29, 1930.

In accordance with my invention, I have replaced the standard breast roll by a small diameter roll 20 which is carried on the ends of the two side bars 14 by means of suitable bearing supports 21. This roll 20 may have substantially the same diameter as the table rolls 12, or, as shown in Fig. 1, it may be somewhat larger so as to give adequate support for the wire bending over its surface. The roll 20, herein termed the first roll, is located close to the first table roll 22, and that distance may be such as to provide substantially the same spacing between the lines of contact of the two rolls with the wire as is had between the second and third rolls and the others of the series. This insures holding the wire substantially in its plane where the stock first flows onto it. To permit this close and equalized spacing, the first roll 20 has a diameter of not substantially greater than twice that of the other table rolls; and its bearing mount is so arranged as to permit it to be mounted close to the next table roll.

The return wire roll 24 is located, in the construction of Fig. 1, on a separate bearing mount 25 carried by the floor or the base of the machine; and provision is made for oscillating this roll the same as are the table rolls oscillated when the wire is shaken. This roll 24 may be of large diameter, such as at least 24 inches, so as not to bend the wire detrimentally as it passes therearound in its return path from the couch roll end of the machine. The roll 24 may be located in any convenient location. It need not be close to the other rolls, since the run of wire between the rolls 20 and 24 does not carry the paper stock. But, as shown, this roll 24 is out of the way and cannot interfere with the fibre laying operation. It is best located well beneath the plane of the top run of the wire and in front of the side bars 14 and frame 16 and so that the wire returning from the couch roll may travel beneath the machine frame in a direct run to the roll 24. Various expedients may be adopted, such as are shown in the patent to Berry, No. 1,880,685 of October 4, 1932, for mounting and swinging this return wire roll 24 to a second position, where the wire is slackened and may be readily removed and replaced as is occasionally required.

A further feature of this construction comprises

having the rigid bottom slice plate 30, over which the paper pulp stock flows onto the wire 10, so located that the stock is discharged substantially in the plane of that wire, and preferably at a point

5 which is substantially over the center line of the first table roll 20 or the first roll which supports the wire in its operative plane. In this construction, a thin flexible slice plate 31 is adjustably mounted, such as is shown in the patent to Vedder, 10 #1,734,929 of November 5, 1929, on the front wall 15 of the head box and arranged to regulate the flow of pulp stock. The slice plate may be bent upwardly and locally by a set of screws 32 pivoted thereto. Each screw is supported by a strut bar 33 and positioned by nut 34 and lock nut 35.

The rigid bottom slice plate 30, which serves as a continuation of the bottom board 35 of the head box, has a thin lip 36 at its forward edge located quite close to a vertical plane passing through the axis of the roll 20. This is permitted by the small diameter of the roll 20; whereas if the roll were of the usual large size of the standard breast roll, this slice lip 36 would have to be located at a considerable distance from that plane. 20 The end 37 of the bottom 35 may therefore be made blunt and of thick material of sufficient strength and rigidity for the purpose, and yet the thin lip 36 will not project materially beyond the supporting end 37.

25 Because of this arrangement and the sizes of the parts, the stock may flow in the plane of the top run of the wire 10. Also, the stock does not issue onto the upwardly inclined portion 38 of the wire and so be obliged to travel uphill. As shown 30 in the drawings, this rigid bottom slice plate 30 is substantially tangential to the top of the roll 20. Moreover, the wire between the first and second table rolls is of such short length that it will not sag materially under the weight of the pulp stock 35 flowed onto it, and it is not necessary to support the wire on any wire board placed thereunder. Since the rigid bottom slice plate is substantially horizontal and does not slope downwardly, the pulp will not impinge on the wire at an angle; 40 hence this arrangement involving a small first table roll and a rigid bottom slice plate leading the stock to the wire substantially in the plane thereof insures laying the fibres on the wire in a satisfactory arrangement.

45 In the modification shown in Fig. 2, the return wire roll has been replaced by a set of three rolls of smaller diameter than the standard breast roll. These rolls may be conveniently located forward of the table rolls. As shown, 50 the upper roll 40 may constitute the first table roll, and the other two are arranged out of the plane of the table roll section of wire. An intermediate roll 41 takes the most of the bend of the wire and a bottom roll 42 receives the 55 wire as it comes from the couch end of the machine. These three rolls may be suitably mounted, such as on a frame or spider 44 having three arms. In order that the wire may be held taut or loosened, the intermediate roll 41 is mounted for movement relative to the axial 60 plane of the other two. This may be accomplished by revolving the spider 44 so as to swing the roll 41 towards the rear. To this end, the spider 44 is pivotally mounted on a bearing support 45 carried by the side frames 46 of the 65 machine. The top roll 40 may have substantially the same diameter as that of a table roll 48, or is preferably somewhat larger, but not materially more than twice the diameter of the table 70 roll. Hence the first roll 40 may be located close 75 to

to the adjacent table roll for the purpose of preventing sag of the wire where the pulp stock issues onto it. The apron 49 is also positioned as described with reference to Fig. 1.

In this construction, the spider 44 may be swung about its axis on pivot 45, in order to slacken the wire and permit its ready removal. That is, when the roll 41 has been moved into the dotted line position or 180° from its normal operative position, the wire at the top of its run is supported on the roll 42 the same as originally carried by roll 40, and the roll 41 has been removed from contact with the wire. Thus, I have not only satisfied the requirements as above discussed for preventing any sag in the wire while the stock first flows thereon, but I have also provided a very simple construction which provides for removal of the wire. The rolls 40, 41 and 42 are mounted on the frame 46 and so shake along with the table rolls 48. The spider may have a revoluble sleeve 49 eccentrically carrying the pivot shaft 45 which is so arranged that by revolving the sleeve the spider may be lowered somewhat and thus drop the top roll 40 below the plane of the wire and aid in loosening and removing the same.

The operation of a paper making machine embodying my invention is obvious, in view of the above disclosure. In each of these constructions, the pulp stock flows onto the top of the first roll 20 or 40 in the table section; and the distance between that first roll and the next table roll is substantially the same as that between any other two adjacent table rolls, so that the wire does not sag materially where the heavy stock first strikes it. This is made possible by having the first roll 20 or 40 of a comparatively small size, so that it may be arranged close to the next roll. In some constructions the table rolls are substantially in contact. Hence the first roll should be small, as compared to the diameters of the others, so as not to spread the supports of the wire at this critical point where the stock flows onto it. This is permitted by having the return wire roll 24 of Fig. 1 arranged at a substantial distance away from the table roll section. This is also permitted in the construction of Fig. 2 by having the return wire roll 40 in the table section of a comparatively small diameter. The combination of the three rolls 40, 41 and 42 takes the place of a large return wire roll or breast roll, as is commonly used. The rolls 41 and 42 may also be made of small diameter, since the wire is bent progressively as it passes around these rolls. These rolls 40, 41 and 42, as well as rolls 20 and 24 of Fig. 1, have a capillary and drying contact with the wire. A larger number of return wire rolls may be provided, if desired, to effect a more gradual bending of the wire. By this arrangement, I make it possible to have a small return wire roll in the table section and yet not injure the wire by bending it too rapidly.

It will now be understood that various modifications may be made and equivalent constructions substituted for the parts herein described. Hence, the above disclosure is to be interpreted as setting forth the principles of this invention and two preferred embodiments thereof and not as imposing limitations on the claims appended hereto.

I claim:

1. A Fourdrinier paper making machine comprising table rolls carrying the table section of

the wire in substantially a plane, means including shakable side bars for rotatably supporting the rolls in a spaced axially shakable relationship and providing for unobstructed drainage therebetween of water passing through the shaking wire, a head box for paper pulp having a rigid bottom slice plate substantially tangential to the first roll and an adjustable slice plate thereabove arranged for flowing the pulp onto the wire in substantially said plane and in a regulated flow, a first roll having a diameter of not more than about twice that of a table roll and which is located close to the adjacent first table roll so that they support the wire in substantially said plane under the weight of the pulp, a return wire roll having its front located beneath and forward of the first roll which makes a drying contact with the returning wire and delivers it to the first roll, the discharge edge of said bottom slice plate being located close to the top of said first roll to cause the stock to issue directly onto the wire substantially over said first roll.

2. A Fourdrinier paper making machine as specified in claim 1 comprising means for adjustably moving the return wire roll to and from normal operating positions without disturbing the first roll and the table rolls.

3. A Fourdrinier paper making machine as specified in claim 1 comprising a movable mount for the return wire roll and the first roll which moves them together from their operative wire supporting positions for loosening and removal of the wire.

4. A Fourdrinier paper making machine comprising means including table rolls for supporting the wire in substantially a plane and providing unobstructed drainage of water passing through the wire, a head box having slice plates arranged for regulatably flowing pulp directly onto the wire, a set of return wire rolls arranged with their axes in different horizontal planes and with the upper roll forming a first roll that supports the wire in substantially said plane in advance of the first table roll, and a revolvable frame supporting the return wire rolls which provides for movement of the rolls to and from their operative wire supporting positions.

5. A Fourdrinier paper making machine according to claim 4 in which the set of return wire rolls comprises two rolls having their axes one above the other and a third roll located between and forward of the other two and about which the returning wire changes in direction and passes towards the table rolls, and wherein the frame is revolvable to move said third roll to a position where the wire is loose while supported in position by the other two rolls.
